UNITED STATES PATENT OFFICE.

ZVETKO ORIZAROFF, OF HARRISBURG, PENNSYLVANIA.

DESIGN FOR A PICTURE-HOLDER.

52,177.

Specification for Design.

Patented July 16, 1918.

Application filed April 27, 1918. Serial No. 231,264. Term of patent 14 years.

To all whom it may concern:

Be it known that I, ZVETKO ORIZAROFF, a citizen of the United States, residing at Harrisburg, in the county of Dauphin and State of Pennsylvania, have invented a new, original, and ornamental Design for a Picture-Holder, of which the following is a specification, reference being had to the accompanying drawing, forming part thereof.

The figure is a front elevation of a picture holder showing my new design.

I claim:

The ornamental design for a picture holder, as shown.

ZVETKO ORIZAROFF.

Witnesses:

H. EDWIN PARSON,
S. H. ZIMMERMAN.
